ATTORNEY

UNITED STATES PATENT OFFICE.

CHARLES D. JARVIS, OF SAN FRANCISCO, CALIFORNIA.

AUTOMATIC AIR-PRESSURE EQUALIZER.

Application filed June 24, 1926. Serial No. 118,302.

This invention relates to improvements in air pressure equalizing devices for the compressed air supply of Diesel engines, my principal object being to provide an automatically operating means for preventing the air pressure in the compressor tank from rising above a predetermined pressure.

Engines of this character utilize compressed air for various purposes, such as starting fuel feeding and scavenging, as well as for operating the whistle if the installation is on a boat, and are provided with air compressors operated by the engines themselves.

The pressure in the tank is therefore being continuously built up as long as the engine is in operation, and very frequently such pressure is not used up as fast as it accumulates. Some means must therefore be provided to prevent excessive air pressure from developing in the tank. Safety or blow-off valves of the usual character are objectionable since they make a loud hissing or whistling sound when in operation.

Manually operated relief valves are also objectionable since if the operator fails to note an excessive pressure and open the valve when necessary an explosion of the tank is liable to occur.

The air compressors are each provided with an intake valve automatically opening with the suction stroke of the compressor piston and automatically closing during the pressure stroke of the piston, and my attachment provides means operated by the air pressure itself for holding this valve constantly open when the air pressure in the tank exceeds a predetermined amount. This of course neutralizes the compressive action of the piston and no air will be delivered to the tank until the valve is again allowed to function in the normal manner.

A further object of my invention is to provide a device for the purpose which may be readily installed in connection with an air compressor having the above type of valve without necessitating any change or alteration in such valve or compressor being made.

A further object of the invention is to produce a simple and inexpensive device and yet one which will be exceedingly effective for the purpose for which it is designed.

These objects I accomplish by means of

such structure and relative arrangement of parts as will fully appear by a perusal of the following specification and claims.

In the drawings similar characters of reference indicate corresponding parts in the several views:

Fig. 1 is a sectional elevation of my improved valve controlling attachment shown as installed in connection with a compressor head.

Fig. 2 is a diagrammatic view showing the compressor, air tank, and valve controlling features as connected up.

Referring now more particularly to the characters of reference on the drawings, the numeral 1 denotes the air compressor of the engine having a reciprocating piston 2 therein which is operated by a connecting rod 3 driven continually with the operation of the engine in the usual manner. In the head 4 of the compressor is a downwardly opening intake valve 5 of the poppet type having a stem 6 projecting upwardly through the head. The valve is normally held seated by a spring 7. A pressure pipe 8 leads from the compressor 1 to a reservoir or tank 9 so that with the operation of the engine and compressor air will be constantly delivered under pressure to the tank. The valve 5 is opened during the suction stroke of the piston and automatically closed on the pressure stroke of the piston, but if the valve is constantly held open it will be evident that such pressure stroke will not cause any air to be delivered to the pipe 8 and the tank.

My air pressure equalizing device for automatically holding the valve open when the pressure in the tank exceeds a predetermined amount comprises a barrel 10 disposed in vertical alinement with the stem 6. The barrel is held rigidly in position by a bracket member 11 clamped thereto and secured to the compressor head 4. A stem 12 alined with the valve stem 6 is slidable through a combined adjusting nut and bearing member 13 mounted in the bottom of the barrel. The end of the sleeve 12 adjacent the valve stem has a head in the form of an adjustable nut 14 so that the normal distance of said nut from the stem 6 may be regulated to suit.

The upper end of the stem 12 inside the barrel has a fixed head 15, a compression

spring 16 being disposed about said stem between the nut 13 and head 15 and tending to force said stem upwardly.

Removably screwed into the top of the barrel is a cylinder 17 into the upper end of which is secured one end of an air pipe 18 leading thence to the tank 9. A union 19 is interposed in this pipe intermediate its ends and also a shut-off valve 20 disposed 10 between the union and the tank 9.

Slidable in the cylinder and normally bearing at its lower end against the head 15 is a piston or plunger 21. The piston has an enlarged portion 22 intermediate its 15 ends which is slidable through an adjustable packing nut 23 mounted in the lower end of the cylinder. Surrounding the piston above said enlarged portion are packing rings 24, the upper end of the portion 22 20 normally engaging the lowermost ring. The spring 16 constantly acts to force the stem 12 and the piston 21 upwardly, and such movement is of course limited by the engagement of the member 22 with the rings 24, 25 which also causes the rings to be squeezed against the piston to aid in maintaining an air-tight seal.

After the structure is assembled in position the head 14 is adjusted so that it clears 30 the valve stem sufficiently to allow proper seating of the valve. The pressure of the spring 16 is also adjusted by turning the nut 13 so that the spring pressure holding the stem 12 away from the valve stem will be 35 equal with the pressure desired to be maintained in the tank 9 before the compressor valve becomes held open. Even though the air pressure is constantly in the pipe 18 and bears against the top of the piston, no downward movement of said piston will therefore be had until the air pressure overcomes 40 that of the spring. The valve will then be opened and held open until the air pressure in the tank is reduced, with the using of the air, to a point where such air pressure is 45 less than that of the spring. The latter then acts to raise the stem 12 and the piston, so as to withdraw the stem 12 from engagement with the valve stem and permitting the 50 valve to seat. The compressor will then function to again deliver air to the tank.

By providing a union in the pipe 18 and mounting the cylinder detachably on the

barrel, said cylinder and piston therein may be easily removed as a unit without disturbing the barrel and other parts, so as to enable the packing structure to be adjusted or replaced when necessary.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. An automatic air-pressure equalizer including a stem adapted to engage and open the intake valve of an air compressor, a plunger separate from and aligned with the stem to engage one end of the same, an enlargement on the plunger, a cylinder in which said plunger is slidable, packing rings about the plunger just beyond the end of the enlargement opposite to the stem, and a spring acting on the stem to force the same into engagement with the plunger, whereby the enlargement will then tend to compress the rings and force the same into constant air-tight engagement with the plunger. 85

2. An automatic air-pressure equalizer including a stem adapted to engage and open the intake valve of an air compressor, a plunger separate from and aligned with the stem to engage one end of the same, a barrel in which the stem is slidable and a cylinder in which the plunger is mounted detachably on the barrel. 90

3. An automatic air pressure equalizer comprising a stem arranged to engage and open a valve; means normally holding the stem from such engagement, a barrel in which the stem and said means are mounted, the barrel beyond the outer end of the stem being arranged for connection to a fluid-pressure pipe, and means for supporting the barrel to maintain the stem therein in definite alignment with the valve. 100

In testimony whereof I affix my signature.

CHARLES D. JARVIS.

CERTIFICATE OF CORRECTION.

Patent No. 1,651,773.

Granted December 6, 1927, to

CHARLES D. JARVIS.

It is hereby certified that error appears in the printed specification of the above numbered patent requiring correction as follows: Page 2, line 93, claim 2, before the word "on" insert the word "mounted"; and that the said Letters Patent should be read with this correction therein that the same may conform to the record of the case in the Patent Office.

Signed and sealed this 17th day of January, A. D. 1928.

Seal.

**M. J. Moore,
Acting Commissioner of Patents.**
